CLAIM

The ornamental design for a terminal, as shown and described.

DESCRIPTION

This design is installed and used to the surface of a wall of the inside/outside of a house or the inside of a switch box of various machines.

FIG. 1 is top, front and right side oblique view of a terminal showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line portion of FIG. 7 is included to show unclaimed internal subject matter only and forms no part of the claimed design.
